UNITED STATES PATENT OFFICE

170,592

SOCK OR SIMILAR ARTICLE

Lionel Lasar, Lynbrook, N. Y.

Application March 23, 1953, Serial No. 24,155

Term of patent 3½ years

(Cl. D47—7)

To all whom it may concern:

Be it known that I, Lionel Lasar, a citizen of the United States of America, residing at Lynbrook, in the county of Nassau and State of New York, have invented a new, original, and ornamental Design for a Sock or Similar Article, of which the following is a specification, reference being made to the accompanying drawing, forming a part thereof.

Fig. 1 is a side view of a sock, embodying my new design; and

Fig. 2 is a view of the opposite side thereof.

I claim :

The ornamental design for a sock or similar article, substantially as shown.

LIONEL LASAR.
